UNITED STATES PATENT OFFICE.

HENRY F. BECHMAN, OF BATTLE CREEK, MICHIGAN, ASSIGNOR TO DUPLEX PRINTING PRESS COMPANY, OF BATTLE CREEK, MICHIGAN, A CORPORATION OF MICHIGAN.

SINGLE-PLATE ROTARY PRINTING-PRESS.

979,919.

Specification of Letters Patent. Patented Dec. 27, 1910.

Application filed March 15, 1909. Serial No. 483,600.

To all whom it may concern:

Be it known that I, HENRY F. BECHMAN, of Battle Creek, in the county of Calhoun and State of Michigan, have invented certain new and useful Improvements in Single-Plate Rotary Printing-Presses; and I hereby declare that the following is a full, clear, and exact description thereof, reference being had to the accompanying drawings, which form part of this specification.

This invention relates to rotary-cylinder web-printing presses especially adapted for printing newspapers, and wherein the printing surfaces are formed on stereotype plates fastened upon the peripheries of the plate cylinders and co-acting with adjacent impression cylinders to print a web.

The primary object of the present invention is to provide means for quickly and easily placing on the cylinders and fastening in position the tubular plates used on the single-plate press described in my Patent Number 867,230 dated October 1, 1907, and the chief advantage of the present invention is that it permits the slipping of such plates onto such cylinders without in any way disturbing the adjustments of said cylinders.

The present invention in particular is an improvement upon the press shown in my Patent No. 867,230 dated October 1st, 1907.

A particularly noticeable feature of my press is that the plate and impression cylinders are of very small diameter, so that an ordinary newspaper-page plate will practically surround the circumference of the cylinder, and the press is designed for use with tubular stereotype plates, each plate containing but one newspaper page of matter; and the press is so constructed that such small tubular plates may be slipped endwise on and off the plate cylinders without removing the cylinders from their bearings, and without disturbing the cylinder bearings or their adjustment in any way. This is one very important practical feature of the invention, and greatly facilitates making ready the press.

Another novel feature of the press is the means for fastening the tubular plates on the cylinders.

In the accompanying drawings I have shown the invention as embodied in a press having four rotary perfecting mechanisms; in which each plate cylinder is adapted to

carry two tubular single page plates arranged end to end thereon, so that each perfecting mechanism will print four newspaper pages, the total capacity of such press being therefore sixteen pages. The total capacity of such a press can however be easily increased by lengthening the cylinders so that they can carry three or more tubular page-plates; or by adding additional perfecting mechanisms; or diminished by corresponding reductions in the machine. The several perfecting mechanisms are all constructed alike so that the description of one will explain all.

I will now describe the invention more in detail, as embodied in the press shown in the accompanying drawings, and will refer to the claims following such description for summaries of the parts and combinations of parts for which protection is desired.

In said drawings—Figure 1 is a side elevation of a press embodying the invention. Fig. 2 is an enlarged end view of one set of cylinder bearings. Fig. 3 is a top plan view of such bearings. Fig. 4 is a sectional view of one of the plate cylinders and a tubular plate thereon. Fig. 5 is a diagrammatical longitudinal sectional elevation of the press. Fig. 6 is an enlarged sectional elevation of one of the plate cylinders. Figs. 7 and 8 are detail sectional and top views of one of the plate cylinders showing the plate fastenings. Fig. 9 is a detail section of a plate cylinder showing the end plate fastening device in retracted position. Fig. 10 is an enlarged detail section on line 10—10, Fig. 6. Fig. 11 is an enlarged detail section on line 11—11, Fig. 6. Fig. 12 is an enlarged detail section on line 12—12, Fig. 9.

The press as shown in Fig. 1 has four perfecting mechanisms A, B, C, D, which are arranged in two decks or planes, with two perfecting mechanisms in each deck. Each perfecting mechanism comprises two plate and two impression cylinders, which in this instance are shown as extending transversely of the press and arranged in the same horizontal plane, the plate cylinders 1, 1^a, being outermost and the impression cylinders 2, 2^a, lying intermediate the plate cylinders. A striking feature of the press is the diminutive size of these cylinders; in practice they are only half the diameter or less of the plate and impression cylinders employed.

in the ordinary rotary web presses; the circumference of each plate cylinder when the plate is on in my press being merely equal to the length of one newspaper page—plus the desired margins between successive impressions,—whereas in ordinary presses the circumference of the cylinders is at least twice as great. With such small cylinders I use tubular stereotype plates each of which 10 contains but one newspaper page of matter, and practically surrounds the circumference of the cylinder, one such plate being shown at P in the drawings, see Figs. 4, 5 and 6. These plates (see Fig. 4) are practically 15 cylindrical tubes, but have a narrow slot p formed by the margin spaces of the page, which slot equals in width the desired distance between successive impressions on the web; this slot p moreover corresponds in 20 width to the width of a longitudinal rib 1^b on the plate cylinder, which rib and slot insure the necessary space between successive 25 impressions on the web produced by the plate to give the proper marginal cut between the papers. Such plates P can be placed on or removed from the cylinders only by slipping them endwise on or off the cylinders; but this can be done without disturbing the bearings or adjustment of the 30 cylinders in a very rapid manner by reason of the novel construction of the cylinder bearings.

Preferably the plate and impression cylinders are all journaled in common bracket casting 3, each of which is provided with aligned bearings for the journals of the plate and impression cylinders, such bracket castings being rigidly bolted to the side frames of the press. The bearings 3^a for the plate cylinders are practically circular and of an exterior diameter less than the diameter of the plate cylinders. Each bearing 3^a is connected with the bearing 3^c of the adjacent impression cylinder by means of a single 45 lateral web 3^b which is of a thickness slightly less than the width of the slot p in the plates. The bearings 3^c for the impression cylinders are connected at top by a web 3^d; all the bearings in a set are preferably 50 cast integral with a base 3^e which is provided with suitable holes for the passage of bolts by which it is secured to the side frame of the press. The plate cylinders are mounted 55 in bearings which are supported by the webs 3^b; and these webs are located between the bearings of the plate and impression cylinders in the plane of the line of impression pressure so that no matter what the impression pressure may be it cannot deflect or 60 distort the relative positions of the plate and impression cylinder bearings.

In order to put the plates P upon the cylinders 1, 1^b, the plate cylinders are turned until their ribs 1^b coincide with the webs 3^b of the bearings, then the tubular plates P

are slipped endwise over the bearings 3^a onto the plate cylinders (see Fig. 2); the slots p in the plates permitting them to be slipped past the webs 3^b and the ribs 1^b. Each plate is bored to fit closely and neatly around the periphery of the cylinder and it is trimmed so that the edges of the slot p lie close against the edges of the rib 1^b, and said rib forms an abutment on the cylinder to prevent the plates turning thereon, and it holds them in proper alinement thereon, and also forms an abutment by which the plates are caused to turn with the plate cylinders.

It will be obvious from the foregoing that the plates can be placed on or removed from the cylinders without disturbing the cylinder bearings in the least; and such tubular plates can be handled more readily than the ordinary semicircular plates and are naturally retained on the cylinders by their close fit thereto; and the fact that they surround the same. The only fastening devices required are means for preventing lateral movement of the plates on the cylinders during the operation of the press.

In order to facilitate securing the plates on the plate cylinders or removing them therefrom I have provided such cylinders with novel plate securing devices which are adapted to disappear when disengaged from the plates, and to come into locking position when the plates are placed on the cylinder. I will now describe these devices.

In the press shown the plate cylinders are but two pages wide and both plates can be 100 conveniently slipped on or off the same end of the cylinder; each plate cylinder is provided with one or more slots 1^e in which is placed an ordinary plate clamp or slide block 1^f which is held in the slot by dove-tail or lateral flanges as usual. The inner end 1^g of this slot is deepened and inclined and the dove-tail groove or grooves are inclined inwardly toward the axis of the cylinder so that when the clamp is moved outwardly in the slot the clamp 1^f moves inward and disappears below the surface of the cylinder (see Fig. 7); but when the clamp is moved toward the other end of the cylinder it will rise in the slot and appear 115 properly above the surfaces thereof (see Fig. 6). To the clamp block 1^f is attached a rod 1^h which extends in a narrow elongation of the slot toward the end of cylinder and is provided with a finger 1ⁱ on its extremity which projects sufficiently above the surface of the cylinder to engage the edge of a plate being slid on the cylinder. Before the first plate is placed on the cylinder the clamp 1^f is drawn back into the lower portion of the 120 slot and disappears as described (see Fig. 7); then a plate P is slipped on the cylinder and as it is slid inwardly thereon its forward edge engages the finger 1ⁱ and forces rod 1^h back, causing clamp 1^f to rise beside and 125 130

against the inner edge of the plate (see Fig. 6). Then when the second plate P is slid on the cylinder it catches the clamp 1^e and causes it to move the first plate on until it abuts against a stop 1^w on the cylinder by which it is arrested in printing position. The second plate P is then clamped against linear movement on the plate cylinder by means of a slide block or clamp 1^f (Figs. 12-9) which is sprung on a bolt 1^f which has a bearing through the head of the cylinder and lies in a slot 1^k in the cylinder, said slot 1^k being dove-tailed or undercut at 1^m for engagement of the fingers on the sides of the clamp 1^f; the outer end of the slot has an enlargement 1° and when the clamp is backed out into this enlargement it will turn over into the position indicated in Figs. 9 and 12 so that it disappears below the surface of the cylinder; in which position the plates P can be easily slid on or off the cylinder.

After both plates have been slid on the cylinder as described, the bolt 1^f is turned so as to first bring the clamp 1^f into position to enter the grooved portion of the slot 1^k and so that it projects above the surface of the cylinder, and then the bolt moves the block inward against the edge of the second plate P and forces the latter to cause clamp 1^e to force and hold the first plate in position. Thus it is practically only necessary in securing the plates on the cylinder to operate bolts 1^f as the intermediate clamps 1^e will be automatically positioned by the act of slipping the first plate on or off the cylinder. Each plate cylinder is provided with a rotary inking mechanism which may be of any suitable kind and which are simply indicated at I in the drawings, as they form no part of the present invention, and it is unnecessary to describe same in full herein, as various kinds of well-known inking apparatus could be employed with the plate cylinders.

In the press shown four webs are employed each of which is or may be two-pages wide corresponding in width to the length of the page forms on the plate cylinders 50 which operate thereon. In the present instance each plate cylinder is supposed to carry two tubular page plates. If all four perfecting mechanisms are used the total maximum product of such press at each 55 operation would be sixteen pages. The web a may be led from a roll at one end of the press over suitable guides a', a², a³, to and between the plate and impression cylinders in mechanism A; and then over suitable 60 guides a⁴, a⁵, a⁶, to a roller f at the top of a folding mechanism F at the opposite end of the press. In a like manner web b may be led from a roll at one end of the press over suitable guides b', b², b³, to and between the plate and impression cylinders in 65

mechanism B and then over suitable guides b⁴, b⁵, b⁶, b⁷, to the roller f at the head of the folder F at the opposite end of the machine. The web c may be similarly led from a roll at one end of the machine over suitable guides 70 c', c², c³, through the perfecting mechanism C and then over suitable guides c⁴, c⁵, c⁶, c⁷ to the roller f above the folder. Similarly a web d may be led from a roll at one end of the press over suitable guides d', d², d³, 75 to the perfecting mechanism D and thence over suitable guides d⁴, d⁵, d⁶, to the roller f at the top of the folder. It will be observed that each web passes without any lateral or edgewise deflection from the roll to 80 the folder.

The cylinders in each perfecting mechanism are intergeared as usual to rotate at the same peripheral speed, and they are also adapted to be driven by suitable gearing, not 85 shown, from a common drive shaft; it is unnecessary to illustrate this gearing as it can be varied according to the speed desired, and it will be readily understood and applied by any press builder. It will be understood that any one or more of the perfecting mechanisms can be put out of operation when desired, by simply throwing out 90 the master gear of the train connecting it with the main driving shaft, as in a manner well understood by pressmen. In this way papers of any desired size up to the total capacity of the press can be printed, without 95 necessarily running any unused printing mechanisms.

The press threaded as described can print as many as sixteen full-size pages at each 100 operation in one color, but it is obvious that it can print a less number of pages in multicolor by leading one web through two or more of the perfecting mechanisms, for instance web a after being perfected in one color in mechanism A could be directed over 105 guide c³ to mechanism C and printed in multicolor and then can be led if desired direct to the folder like web c, or it may be directed to and through another perfecting mechanism.

It will be obvious that with such a press 110 it is possible to produce various sizes of papers in color, or multicolor, or in combinations thereof, as desired. By using a half width web, and only one single page plate on each cylinder in any perfecting mechanism, two pages can be printed, and such single page web can be assembled with other webs at the folder. In this way six, ten, and 115 fourteen page papers can be easily produced on this machine.

If the cylinders should be made three-page 120 plates long the press described would be capable of printing a maximum of twenty-four pages in one color, without any additional mechanisms. The capacity of the press can also be increased by adding addi- 125

tional perfecting mechanisms either in the same decks, or by placing them in additional decks, so that all the webs from such additional perfecting mechanisms can be assembled at the folder. If the plate cylinders were made four pages long the capacity of each perfecting mechanism would be increased to eight pages.

It will be obvious that with this press no collecting is necessary; and that only one set of stereotype plates is required, the printing being done on the straight run without collecting; whereas with the ordinary perfecting rotary cylinder web press it is necessary to use a double set of plates when printing on the straight run. With my press I can print as rapidly with one set of plates as can be done on the ordinary rotaries with two sets of stereotype plates, thus effecting a great saving in material, and in labor and time in making ready the press.

Having described my invention what I claim as new and desire to secure by Letters Patent, thereon is:

25 1. In a rotary printing press the combination of a plate cylinder having a narrow longitudinal rib or abutment, and a tubular stereotype plate adapted to encircle the cylinder and having a narrow longitudinal slot 30 adapted to engage the rib on the cylinder when the plate is slipped endwise thereon, whereby said plate is locked against rotative movement on the cylinder.

35 2. In a rotary printing press the combination of a plate cylinder having a narrow longitudinal rib or abutment, with a tubular single page stereotype plate adapted to surround the cylinder and having a single narrow longitudinal slot adapted to receive the 40 rib when the plate is slipped endwise upon the cylinder, whereby said plate is locked against rotative movement on the cylinder; and means for clamping such plate against endwise movement on the cylinder.

45 3. In a rotary printing press the combination of a plate cylinder, and a bearing for such cylinder supported by a narrow web; with a tubular stereotype plate adapted to substantially encircle the cylinder but having a longitudinal slot whereby it is adapted to be slid endwise past the web and over the bearing onto or off of the cylinder.

55 4. In a rotary printing press, a plate cylinder adapted to carry single page tubular plates, a bearing for such cylinder not exceeding the cylinder in diameter and rigidly supported by a narrow web, in combination with a tubular stereotype plate adapted to substantially encircle the cylinder and having a longitudinal slot whereby said plate can be slid endwise past the web and over the bearing onto or off of the cylinder.

5. In a rotary printing press the combination of a plate cylinder having a narrow longitudinal rib, with a bearing for said cyl-

inder not exceeding the cylinder in diameter, and a web supporting said bearing not exceeding the cylinder rib in thickness; with a slotted tubular plate adapted to encircle the cylinder and to be slid endwise past the 70 web and over said bearing on or off the cylinder when the cylinder rib is in alignment with said web.

6. In a rotary printing press the combination of a plate cylinder having a narrow 75 longitudinal spacing rib, and a bearing for said cylinder supported by a similarly narrow web; with a tubular stereotype plate corresponding in diameter to the cylinder and having a longitudinal slot corresponding in width to said rib and adapted to be slid endwise over the cylinder bearing and web onto or off of the plate cylinder when the rib on the cylinder is in alignment with the web of the bearing.

7. In a rotary printing press the combination of a plate cylinder having a narrow longitudinal spacing rib, a bearing for said cylinder slightly less in diameter than the cylinder and having a rigid supporting web 90 approximately equaling the cylinder rib in thickness; with a slotted tubular plate adapted to substantially encircle the cylinder and to be slid endwise over said bearing on or off the cylinder when the cylinder rib is in 95 alignment with the said web and the tube slot is also in alignment therewith.

8. In a rotary printing press a plate cylinder having a narrow longitudinal spacing rib, a bearing for said cylinder approximately equaling the cylinder in diameter and having a rigid supporting web approximately equaling the cylinder rib in thickness; in combination with a tubular stereotype plate corresponding in diameter to the 105 cylinder and adapted to substantially encircle it, and having a narrow longitudinal slot adapted to accommodate the rib and web, and permit such plate to be slid endwise over the cylinder bearing onto or off of the 110 plate cylinder when the rib on the cylinder is in alignment with the web of the bearing.

9. In a rotary printing press the combination of a set of plate and impression cylinders of small diameter approximately equaling the length of a newspaper page in circumference, each plate cylinder having a longitudinal rib corresponding in width to the desired space between successive impressions on a web, and bearings for said plate cylinders slightly less in diameter than the cylinders and supported by webs of substantially the same width as the ribs on the cylinders.

10. In a rotary printing press the combination of a set of plate and impression cylinders of small diameter approximately equaling the length of a newspaper page in circumference, said plate cylinders having longitudinal ribs corresponding in width to the 120

- desired margins between successive impressions, and a set of bearings for said cylinders, the bearing for the plate cylinders being slightly less in diameter than the cylinders and rigidly connected to the bearings of the impression cylinders by webs of substantially the same width as the ribs on the plate cylinders.
11. In a rotary printing press the combination of a set of plate and impression cylinders of small diameter approximately equaling the length of a newspaper page in circumference, each plate cylinder having a longitudinal rib corresponding in width to the desired space between successive impressions on a web, and bearings for said plate cylinders slightly less in diameter than the cylinders and supported by webs of substantially the same width as the ribs on the cylinders; with tubular stereotype plates each having a longitudinal slot corresponding in width to said webs and ribs and adapted to be slipped onto the cylinders over the bearings when the ribs and webs are in alignment.
12. In a rotary printing press the combination of a set of plate and impression cylinders of small diameter approximately equaling the length of a newspaper page in circumference, said plate cylinders having longitudinal ribs corresponding in width to the desired margins between successive impressions, and a set of bearings for said cylinders, the bearings for the plate cylinders being slightly less in diameter than the cylinders and rigidly connected to the bearings of the impression cylinders by webs of substantially the same width as the ribs on the plate cylinders; with tubular stereotype plates each having a longitudinal slot corresponding in width to said webs and ribs and adapted to be slipped onto the plate cylinders over their bearings when the ribs and webs are in alignment, and disappearing clamps on the plate cylinders whereby the plates may be locked in position thereon, substantially as described.
13. In a rotary printing press the combination of a plate and an impression cylinder, with a bearing for the impression cylinder, and a bearing for said plate cylinder, and a web by which said bearing is suspended from the impression cylinder bearing, said web being arranged in the line of impression pressure between said cylinders.
14. In a rotary printing press the combination of a plate cylinder having a longitudinal rib, a bearing for said cylinder, and a web supporting said bearing, said web being arranged in the line of impression pressure, and not exceeding the cylinder rib in thickness; with a slotted tubular plate adapted to substantially encircle the cylinder and to be slid endwise over said bearing on or off the cylinder when the cylinder rib is in alignment with the bearing web.
15. In a rotary printing press, a plate cylinder, and a single longitudinally disposed rib on the periphery of said cylinder; in combination with a split tubular stereotype plate corresponding in internal diameter to the external diameter of the cylinder and adapted to fit closely around the same, said plate having a longitudinal slot corresponding in width to the rib on the cylinder, and permitting said plate to be slid longitudinally on and off the cylinder when the slot registers with the rib, and said rib serving to lock the plate against rotary movement on the cylinder.
16. In a rotary printing press, the combination of a plate cylinder having a longitudinal rib, a bearing for said cylinder, and a support for said bearing corresponding in width to the rib on the cylinder; with a tubular stereotype plate corresponding in internal diameter to the external diameter of the cylinder and adapted to fit closely thereon and having a longitudinal slot corresponding in width to the rib on the cylinder, said tubular plate being adapted to be slid endwise on and off the cylinder and over the cylinder bearing when the rib is in alignment with the support.
17. In a rotary printing press, the combination of a plate cylinder having a longitudinal spacing rib, a bearing for said cylinder not exceeding the cylinder in diameter, and a web supporting said bearing and corresponding in width to the rib on the cylinder and arranged in the line of impression pressure; with a tubular stereotype plate corresponding in internal diameter to the external diameter of the cylinder and adapted to fit closely thereon and having a longitudinal slot corresponding in width to the rib on the cylinder, said tubular plate being adapted to be slid endwise on and off the cylinder and over the cylinder bearing when the rib on the cylinder is in alignment with the web.
- In testimony that I claim the foregoing as my own, I affix my signature in presence of two witnesses.
